TROPHY BASE

Nicholas F. Tangney, New York, N.Y., assignor to Arlen Trophy Co., Inc., North Plainfield, N.J., a corporation of New York

Application August 11, 1958, Serial No. 52,167

Term of patent 3½ years

(Cl. D29—23)

Fig. 1 is a perspective view of a trophy base showing my new design;

Fig. 2 is a top plan view; and

Fig. 3 is a front elevational view thereof.

The dominant features of my design reside in the portion shown in full lines.

I claim:

The ornamental design for a trophy base, substantially as shown and described.
